CATHODE RAY OSCILLOGRAPH

Max Knoll, Berlin-Charlottenburg, Germany

Original application November 18, 1929, Serial No. 408,006. Divided and this application February 5, 1935, Serial No. 5,136. In Germany December 12, 1928

6 Claims. (Cl. 250—27)

This invention has for its object improvements in cathode-ray oscilloscopes, and is a division of patent application, Serial No. 408,006, filed November 18, 1929, Pat. No. 2,036,532, dated April 7, 1936 to Knoll et al.

According to the invention special means are provided in order to keep the focus—so long as it is not moving at its great recording or scanning speed—diverted from the window or other 10 electron beam receiving member. This may be effected in a manner known per se, by diverting the electronic rays sideways by means of a constant magnetic or purely electrical field or a combination of both. Preferably a plate of beryllium or other substance of low atomic weight 15 may be arranged, against which the rays strike during their diversion, in order to prevent as much as possible the generation of X-rays. For the further protection of the observer and of the 20 photographic layer against X-rays this plate is in turn covered with an envelope of material of high atomic weight, e. g. lead.

According to the invention the protection of the window may be effected by intercepting the 25 electron rays instead of diverting them, i. e. by arranging in the path of the electronic rays a beam intercepting means in the form of a bored-through negatively charged stopping-electrode, the negative charge of which is led off at the beginning of the recording operation. As the cathode-ray oscilloscope which is the subject of the invention is intended to be used for rendering visible or recording extraordinarily rapidly occurring phenomena, or for television purposes, the 30 switching on or off of the diverting or stopping device has to be effected in an extraordinarily short space of time, e. g. in 10^{-6} sec. This problem may be solved by a purely electrical switching device with two stable positions of equilibrium, e. g. 35 by the employment of electron tubes, glow-lamps or spark gaps. The invention provides for this purpose a specially simple and rapidly reacting electron-tube device, which is actuated simultaneously with the start of the voltage to be recorded by the oscilloscope. In this way the 40 voltage of the grid-potential of another valve (the so-called "deflector" tube) can at the same time be maintained at the same value, and its saturation current made to flow through a condenser connected in parallel with the controls, the voltage of which is thus varied proportionally 45 with the time.

With apparatus for picture-telegraphy or television in which the whole area of the picture both 50 in transmitter and receiver is scanned by the

focal spot in a zig-zag path consisting of upward and downward straight-line branches, one set of branches, say the upward, can be described at a constant relatively slow velocity, and the other set, the downward, at a constant relatively high 5 velocity by suitably varying the control voltage, as by charging or discharging inserted condensers by means of a constant current, e. g. the saturation current of electron tubes. This must be effected by employing two different constant intensities of current. Thus only the one 10 set of parallel branches is valid for the chemical and physical effects, in contrast to the hitherto-used sinusoidal records, in which, on each of both branches, the recording velocity and the 15 distance from the neighboring branch are continually changing.

The cathode-ray oscilloscope forming the subject of this invention can be used in picture-telegraphy and television also in the transmitting 20 station for scanning the picture to be transmitted, and further for frequency-multiplication for secret telegraphy and the like by scanning separated electrodes arranged chess-board-wise behind the window and easily exchangeable.

Since neither for transmission nor reception need any mechanical parts be moved, the new cathode-ray oscilloscope, especially for picture-telegraphy and television offers a number of such 30 important advantages as to enable both these operations to be carried out with hitherto unattainable perfection.

The synchronization which must be maintained 35 between transmitting and receiving apparatus, is obtained with the utmost ease and with absolute exactitude by simultaneously affecting the corresponding controls of the transmitter and the receiver by the voltage either directly by wire, or indirectly by wireless waves.

The recording velocity obtainable is so great 40 that e. g. a picture of 6 x 6 cm. may easily be scanned in $1/1000$ sec., or even in $1/10,000$ sec., and reproduced with sufficient intensity.

If a picture-frequency of not more than 45 pictures per second (which is adequate for the human eye) is required, pictures of such intensity may be obtained, that they may be projected on a much enlarged scale on to a screen and made visible to a large company of spectators.

Picture-telegraphy can be extraordinarily 50 cheapened and its field of application extended beyond all anticipation.

For instance, the transmitting of a picture, which hitherto required about ten minutes, can 55

be reduced to $\frac{1}{1000}$ of a second. An entire news-sheet, for instance, can be swiftly transmitted by picture-telegraphy, provided only the sheets to be transmitted and the receiving film are moved with sufficient velocity.

5 Cinematographic films can be copied by wireless transmission at any distance.

The speed with which the pictures can be scanned in the transmitter and receiver makes 10 it possible to scan, transmit, and reproduce in one continuous line pairs of stereoscopic pictures, so that either static or in process of production plastic picture-telegraphy and plastic television are made possible in the simplest manner by one 15 and the same apparatus.

The extraordinary speed with which a picture 20 can be scanned at the transmitting station and recorded at the reception station, and the possibility of extremely rapid withdrawal of the focus after the picture has been completely 25 scanned, enable also the transmitting and reception devices to be used for super-speed recording of "slow motion" pictures, in which case a much greater number of pictures per second 30 can easily be recorded, than has been possible with "slow motion" apparatus hitherto used.

If a very high number of pictures per second 35 is to be obtained, it is, for instance, only necessary, firstly, in the receiving apparatus, to double the length of the picture, that is to say the sum 40 of the intervals between all the branches of the zig-zag path, so that with a stationary photographic plate one would obtain a distorted picture double the width; and secondly, to run the receiving film constantly at half speed. This gives 45 the "slow motion" pictures, the optical compensation otherwise required being here replaced by the swift withdrawal of the focus.

The invention is exemplified in the drawings.

Fig. 1 shows schematically a cathode-ray 50 oscillograph, such as can be employed for the various above mentioned purposes.

Fig. 2 shows on a larger scale—schematically drawn—an example of the window of a cathode-ray oscillograph used for the transmission of 55 pictures or for television.

Fig. 3 shows a window of the same sort in the receiving apparatus, for the photographic record of the wirelessly transmitted picture.

Fig. 4 shows schematically, how the cathode-ray tube of the transmitter and the cathode-ray 60 tube of the receiver work together in picture telegraphy or television.

Fig. 5 shows on a larger scale a vacuum-proof 65 pliable device for shifting movable parts, such as, e. g., a deflector plate.

Fig. 6 is the schematic representation of a tube 70 for auto-electronic discharge with a cold cathode and supplied with electrostatic concentrating device.

Fig. 7 represents a thermionic cathode-ray tube with an intercepting electrode, the latter actuated by a tip-action electron-tube device.

Fig. 8 shows a connection-scheme for the production 75 of oscillations with linear variations of voltage, as used especially for televisional or picture telegraphic apparatus.

Fig. 9 shows the wave-shape of the linear oscillations produced by means of such a connection.

70 In the cathode-ray oscillograph represented in Fig. 1 the cathode-ray beam is produced in the metallic discharge-tube 1, which serves at the same time as an anode, and into which the cathode 2 is introduced by means of the bushing 75 3. The cathode 2 is connected with the feed-

voltage by means of the rod 3' lodged in the bushing 3. The coil 4 serves to concentrate the ray beam before it passes through the narrow aperture of the diaphragm 5 into the actual diversion-chamber 7 and onto the electro-permeable 75 window 6.

8, 8' are the deflector plates, which can be adjusted under a high vacuum with the help of elastic bodies 9 or membranes 10 by means of screws 11, which are lodged in supporting tubes 10 12. 15 is a spy-hole, through which the oscillogram to be recorded can be observed also while the photographic record is being taken, provided that the inner side of the electron-permeable layer 6 or parts of the grid 79 are overlaid with 15 a phosphorescent substance. The photographic layer (plate or film 14) is situated during the taking of the record in the shutter 13.

Fig. 2 shows on an enlarged scale in section an example of a photoelectric-cell arrangement for 20 taking pictures. Close behind the electron-permeable window 6, which is also held by the grid 79, is situated the photoelectric mosaic plate 81 of a type generally understood in the art and similar to that shown in the patent to Zworykin No. 25 1,691,324 granted November 13, 1928. This is subdivided by means of insulation-layers indicated in Fig. 2 by the short vertical lines, into as many small fields or photoelectric cathodes as picture stippling points are desired. These small 30 photo-electric cathodes forming the plate 81 are then supplied successively with negative voltage by the electronic beam passing rapidly across them, a resultant current of varying intensity flowing off over the common grid anode 82 to the 35 amplifier 106' (Fig. 4) to provide an amplified modulating current, modulated according to the resistance effective at any given moment dependent on the exposure of the cell in question.

Instead of a photo-electric cell an exchangeable electrode arrangement of any desired formation can also be fixed on the recording apparatus behind the electron-permeable window, enabling a definite succession of current impulses 40 to be sent out for which the receiving apparatus must be arranged accordingly.

A simple method of transmitting pictures also 45 consists in first copying the picture according to a certain process onto a metal plate in such a manner that definite conductivity-values at 50 different points of the surface of the metal plate correspond to the varying intensities of light on different parts of the picture. For example, the 55 picture on the metal plate may be a photographic reproduction in carbon or other resistance substance, or a print made with resistance substance. Some forms of printing ink may have sufficient 60 electrical resistance for the purpose. The electronic beam passing through the electron-permeable window and the resistance image to the 65 plate can excite directly fluctuations of current in the amplifier 106' (Fig. 4) which will serve to vary the intensity of the cathode-ray in the receiver.

A further possible method of application of 70 the invention to picture-telegraphy consists e. g. in utilizing the travelling point of light produced outside the transmitter-tube on the fluorescent screen over a system of lenses for scanning the 75 picture to be transmitted and having the reflected rays gathered up by one single large photo-electric cell.

Fig. 3 shows on an enlarged scale in section an example of the construction of an electron-permeable layer 6 for cathode-ray oscillographs with 75

a supporting grid 78 of metal strips placed edge-wise. The electronic beam when not in use falls behind one of the aluminium blades 88; the X-rays then generated are screened off by a lead 5 mantle 84. The oscillogram or picture appears on a fluorescent layer fixed onto the exterior side of the electron-permeable foil 6. If photographic records have to be made, the light sensitive film or plate 14 is pressed closely onto the electron-permeable window 6 by means of the light-proof shutter 13.

Fig. 4 shows an example of an arrangement for a cathode-ray oscillograph in accordance with the invention, applicable for picture telegraphy and 15 television, *a* denoting the receiver arrangement, *b* the transmitter arrangement; both are, wireless transmission being pre-supposed, connected with each other by way of antennae 91' and 91. For sending and receiving there serve respectively the 20 cathode-ray oscillographs 92' and 92 with hot-cathode discharge devices 93' and 93 respectively, pairs of deflector plates 94', 95' and 94, 95 for producing a scanning movement of the cathode-ray beams of the respective oscillographs and 25 electron-permeable windows 6' and 6. The pairs of deflector plates 94', 95', and 94, 95 respectively shown in the diagram for the sake of clearness as parallel lie in the actual apparatus in each tube in planes at right angles to each other. The feed 30 voltage for the discharge tubes lies at points 97', 98', and 97, 98 respectively.

By means of intercepting-electrodes 99' and 99 respectively, arranged between the hot-cathodes in the tubes 93' and 93 respectively, and the corresponding anode 97' and 97, the generation of 35 electronic-rays during the pauses in the scanning movement as controlled by plates 94', and thereby by the fusing of the window, is prevented in a manner to be hereinafter described. The electrons passing through the electron permeable layer 6' of the transmitter tube 92' fall upon a photoelectric mosaic of known construction 100, the photo-electrically active layer 81 of which is divided in a manner known per se (for example, 40 as disclosed in Patent No. 1,691,329 to Zworykin dated November 13, 1928, and Patent No. 1,780,364 to Reynolds dated November 4, 1930), into a large number of small separate areas shown enlarged in Fig. 2. On the photo-electric layer there 45 is formed by means of lenses 101 according to the known laws of optics, a picture of the object 102 to be reproduced, so that there falls upon each of the areas a definite, in general varying intensity of light. The illumination of each area 50 takes place through the wide-meshed grid 82, which serves as common anode for all the small photo-electric cells. The actual transmission is effected by means of the high-frequency transmitter 103, of any known or suitable form for 55 multiple signal transmission, as for example that described in the Zworykin patent above referred to, and provided with a common transmitting antenna 91' and modulated in known manner by the oscillators 104' and 105' as well as by the 60 fluctuations of the photo-electric cells 81 conducted by way of amplifier 106'. Both oscillators 104' and 105' produce, by means of a device known per se, and represented diagrammatically in Fig. 8, oscillations with a time-proportional 65 voltage-variation of the wave-shape sketched in Fig. 9. In this manner there is insured, in contrast to what happens in the case of the sinusoidal oscillations frequently used for such purposes, a precisely time-proportional scanning of 70 the picture to be transmitted.

The transmission of a picture from the transmitter to the receiver takes place in the following manner:

The deflecting or sweep circuit oscillator 105' produces continuously oscillations of a definite frequency, about 10^5 per sec., which affect the pair of deflector plates 95' of the transmitter tube 92', and are transmitted by way of the high-frequency transmitter 103, the transmitting antenna 91', the receiving antenna 91, and the selective amplifier 105 operating in known manner as for example the selective amplifier 67-71 of the Zworykin patent above referred to, to the pair of plates 95 of the receiver tube 92. When oscillator 105' is alone working, the scanning sweep or 15 oscillations of the electronic beam describe a stationary line equal to the height of the picture to be transmitted, both in the transmitter tube and receiver tube.

If now the deflecting or sweep circuit oscillator 20 104' is also switched on (frequency about 10^3 per sec.), which affects the second pair of deflector plates 94' standing at right angles to 95' of the transmitter tube, these oscillations are transmitted by way of the same path as those from oscillator 105', through a selective amplifier 104, to the pair of deflector plates 94 of the receiver tube 92 and the original line is once again transformed into a progressive zig-zag record. If the frequency of the oscillator 104' is properly adjusted, 30 the record produced has the width of the picture transmitted. If in addition the width of the oscillator 105' is not greater than about the width of the line described by the focus spot, each point of the picture being transmitted, both in the 35 transmitter tube and in the receiver tube, is scanned simultaneously and for an equal period by the cathode-ray beam.

The interception of the electronic beam when not being used is here effected by means of the 40 intercepting electrodes 99 and 99' respectively by way of a—not here shown—tip-action electron-tube device similar to that represented in Fig. 7, which is controlled by means of the oscillator 104' and the amplifier 104 which latter two elements 45 produce the scanning movement of the beams. As the cathode-ray beam on its way through the transmitter tube 92' meets with varying degrees of resistance according to the conductivity of the photo-electric cell with which it happens to be in contact, fluctuations of current take place 50 corresponding to the occurring differences of intensity. These fluctuations are transmitted by way of the amplifier 106', the high frequency transmitter 103', the transmitting antenna 91', 55 the receiving antenna 91, and a selecting amplifier 106, onto the control grid 11 of the receiver tube 92, there giving rise to corresponding fluctuations of the beam-intensity, which in turn cause the requisite fluctuations in intensity of 60 the picture reproduced on the fluorescent screen 6.

The arrangement schematically represented in Fig. 4—both the transmitting and the reception apparatus—allows also in the simplest manner possible of transmitting stereoscopic pictures to 65 any distance and likewise of stereoscopic television. A stereoscopic picture, as is well known, consists of a pair of pictures side by side, representing respectively the right and left eye views of a scene or object. If the window 6' and 6 70 are made so long in one direction, e. g., in a direction perpendicular to the plane of the drawings, that a pair of stereoscopic pictures can be scanned adjacently and adjacently reproduced in the receiver, then both pictures may be scanned 75

by the focal spot in one continuous line in each of both apparatus. The stereoscopic transmission of pictures and stereoscopic television may be thus realised by simply transmitting as a single 5 picture, a pair of stereoscopic pictures side by side. The pair of stereoscopic pictures thus received side by side at the receiving station may be synthesized in known manner.

In Fig. 5 is exemplified on a larger scale the 10 pliable device shown in Fig. 1 employed for shifting movable parts under a high vacuum. The device here serves for the adjustment of the electrostatic deflector-plate 8, by means of the pliable metal body 9 actuated by nut 107, pressing upon 15 the carrier-bush 24. This is joined by means of three screws 25, sliding in slots of the jacket 26, with the guide-ring 27, into which, by means of an insulating washer 29, e. g. of Bakelite, is fixed the supporting rod 28 of the deflector plate 8. 20 The pliable body 9 is joined in a vacuum-tight manner at both ends with its guide-rings, and likewise the insulating washer 29 with guide-ring 27; furthermore the supporting rod 28 is guided by another perforated insulating washer 30. The 25 ring 31 carrying washer 30 is fixed directly into the jacket 7 of the cathode-ray tube.

The tube 32 for auto-electronic discharge shown in Fig. 6 contains an anode 33 and an intercepting electrode (auxiliary anode) 34 which 30 during the release of the beam functions as an anode. The release is effected by two spark gaps or glow-lamps 35 and 36 connected by way of windings 37, 38 with the perforated intercepting electrode 34 and by way of a high resistance element 39 with the cold cathode 40. The high-tension continuous current required for feeding the tube is generated in the known manner by means of transformer 41, valve 42, and condenser 43, the valve 42 acting in known manner as a 40 rectifier permitting current to pass only downwardly therethrough, thus maintaining the condenser 43 charged with the lower plate positive and the upper plate negative. If the gaps 35 and 36 are properly adjusted, any sudden surge 45 of voltage arising from the transmission line or antenna 44 and inducted from the winding 45 according to the polarity of the surge, either onto the winding 37 or 38, causes a sparking of the gap 35 or 36, the duration of which depends upon 50 the value of the capacity 46 and the resistance 47. By this the electrode 34, which has hitherto intercepted the beam, becomes an anode, and the extremely sharp point of the cathode 40 ejects an 55 electronic beam through the perforations in the electrodes 34 and 33, the intensity of the beam can further be varied by means of the controlling electrode 33 by varying the angle of the cone-shaped electronic beam.

In the lower part of Fig. 6 is shown schematically an electrostatic device for concentrating the 60 electronic beam. It consists of cylindrical metal tubes 48, sustained by supports 49 in such a position as to allow of the electronic beam passing freely through it, and of the metal ring washers 65 50 between the tubes 48. If the washers 50 are charged negatively to the tubes 48, divergent electric fields are formed, which exercise a force 60 concentrating radially the beam. Thus an exceptionally minute focal spot is obtained. Adjustment of the voltage applied to the tube and 70 washer elements at the polarity indicated in the diagram, and according to the spacing of the electron-permeable window will bring the rays to a focus at the window, as will be understood by 75 those skilled in the art.

The thermionic cathode-ray tube 51 shown in Fig. 7, is provided with the hot cathode 52, anode 53, and control-grid 54 controlling the intensity of the electrons in the beam while the latter is working. In order to prevent the fusing of the 5 window during periods when the focal spot is at rest, an intercepting electrode 55 is provided, actuated by a tip-action electron-tube device. This device consists of the electron-tubes 56, 57, and 58, the anodes of which are connected on the one hand by way of resistances 59 and 60 with the positive pole of a storage battery, and on the other hand crosswise by way of condensers 61, 62 with the grids of the tubes 56 and 57. Thus far the circuit arrangement is quite similar to the well known multivibrator circuit. However, in the present system the circuit is intended to function not as a multivibrator, but as a trigger or tip-acting device for releasing the blocking charge on the intercepting electrode 55. This change 10 in the function is accomplished by substituting for the usual grid leak between grid and cathode, a battery 63 to the potential of the battery 63 and which by way of the high resistances 64, 65 keeps the condenser 61 charged, the grid potential of the tube 56 at a lower level than the anode potential of tube 57, the amount of the diminution being about the same as the anode potential itself so as to bring the said grid potential to zero or negative. The potential between the grid 15 and filament of tube 56 will be the algebraic sum of the potential of the anode of tube 57 and the battery 63. If the grid of the tube 57, which tube is fully emitting during the interception of the cathode-ray beam, is affected by a surge of negative voltage issuing from the antenna or transmission line 66 by way of the resistances 67 or 68, and by way of the condenser 69, the arrangement tips over into its other position of stable equilibrium. In that case tube 57 is blocked. The grid 20 potential of tube 56 and therewith that of the intercepting electrode, hitherto negative, now receive the same potential as hot cathode 52, or a potential positive to it due to the rise in potential across the terminals of tube 57, and the cathode-ray beam is released. If the surges issuing 25 from the antenna or line 66 are positive, the tube 58 acts in the same manner. By means of resistance 70, the time of the tipping-over of the device back into the position of equilibrium corresponding to the period of interception of the cathode-ray beam may be adjusted at will, thus enabling the release to be maintained for any length of time desired.

Fig. 8 refers to a device suitable for the production of oscillations with linear variation of voltage, such as is provided for the oscillators 104' and 105' in Fig. 4. In Fig. 8, 71 and 71' are triode-valves, fed by the batteries 72 and 72'. By the saturation-current of these valves, the 60 condenser 73 is alternately charged and discharged by way of the resistances 74 and 74'. The charging and discharging is automatically controlled by the grids 76 or 76', the potential of which is maintained at a suitable level by 65 means of batteries 75 and 75'. By varying the capacity of the condenser 73, the required frequency may easily and swiftly be obtained when working.

If the saturation-currents of the valves 71 and 71' are selected at various values, or the resistances 74 and 74' are given different resistivities, the upward branches 77 of the oscillations taking place proportionally with the time (see Fig. 9) become less steep than the downward branches 78. 75

whereby both in the transmitter and in the receiver the effect of the downward branches is diminished in comparison with that of the upward branches.

If the batteries 75 and 75' shown in the connection-scheme Fig. 8 and their connections are omitted, the grid 76' joined with the hot cathode of its tube, and the grid 76 affected by the voltage of a control of the cathode-ray oscillograph, e. g. by the voltage of the oscillator 105' shown in Fig. 4 then to accumulate a definite charge after a given number of impulses from the oscillator 105' a positive dependence is obtained of the control voltage 104' upon the voltage of the control 105'. That is to say, the lengthwise return of the focal spot occurs always after a definite number of transversal oscillations.

I claim:

1. A cathode-ray oscillograph comprising a cathode with means for producing a beam of electron rays, deflecting means to deflect the said beam sideways in one direction with a source of predetermined continuous-wave electrical variations for energizing the same, another deflecting means to deflect the said beam transversely to the said direction with a source of predetermined continuous-wave electrical variations for energizing the same, a receiving member lying in the path of the beam, and means to automatically prevent the rays from striking the said receiving member while one of said beam deflecting means is ineffective to maintain motion of the beam over the receiving member, the automatic means comprising a charged intercepting electrode arranged to be discharged by an electron tip-acting device controlled by the continuous-wave electrical variations of said one deflecting means to repeatedly release and intercept the beam.

2. A cathode-ray oscillograph comprising means for generating a beam of electrons, a receiving member in the path of said beam, a scanning control oscillator for producing predetermined timed electrical variations, deflecting means for moving said beam over said receiving member uninterruptedly from side to side with substantially constant amplitude in response to said electrical variations, means for normally preventing the generation of said beam, and means controlled by said scanning control os-

cillator for rendering said last named means ineffective.

3. In a cathode-ray oscillograph, means for producing a beam of electron-rays, a device for intercepting the rays, a scanning control device for the beam, means for applying electrical energy to said scanning device, a device tip-acting between two positions of stable equilibrium controlling said intercepting device, said tip-acting device being connected for control by the electrical energy supply means for the scanning device whereby the tipping over from one position of equilibrium to the other position is effected by the start of the electrical energy applied to the scanning device, and means for returning the tip-acting device to the previous position of equilibrium after a predetermined interval of time adjustable at will.

4. A cathode-ray oscillograph comprising means for generating a beam of electrons, a receiving member in the path of said beam, means for intercepting the beam, beam deflecting means, a signal circuit, a deflecting control circuit separate from said signal circuit, said intercepting means being operatively connected with said deflecting control circuit for control thereby independently of said signal circuit.

5. A cathode-ray oscillograph comprising means for generating a beam of electrons, a receiving member in the path of said beam, means for intercepting the beam, beam deflecting means, a signal circuit, a deflecting control circuit separate from said signal circuit and including means for producing electrical variations for effecting a predetermined time-proportional scanning movement of the beam independently of the electrical condition of the signal circuit, said intercepting means being operatively connected with said deflecting control circuit for control thereby independently of said signal circuit.

6. A cathode-ray oscillograph comprising means for generating a beam of electrons, a receiving member in the path of said beam, means for intercepting the beam, beam deflecting means, a signal circuit, a deflecting control circuit operatively separate from said signal circuit, and common control means for controlling said intercepting means and said beam deflecting means.

MAX KNOLL. 50
